PLASTIC PLACE MAT

William E. Cole, London, England

Application November 14, 1956, Serial No. 43,765

Term of patent 14 years

(Cl. D3—9)

The single figure is a plan view of a plastic place mat showing my new design.

The place mat is shown over a dark background to bring out the details of the design.

I claim:

The ornamental design for plastic place mat, as shown and described.
